(57) **CLAIM**

The ornamental design for a shoe heel resembling a taxicab, as shown and described.

DESCRIPTION

FIG. 1 is a perspective view of a shoe heel resembling a taxicab, shown attached to a shoe.

FIG. 2 is a perspective view thereof, shown attached to a shoe.

FIG. 3 is a right side elevational view thereof, shown attached to a shoe.

FIG. 4 is a right side elevational view of the portion of the shoe heel resembling a taxicab indicated by the box 4 in FIG. 3.

FIG. 5 is a left side elevational view of the shoe heel resembling a taxicab of FIG. 1, shown attached to a shoe.

FIG. 6 is a back elevational view thereof, shown attached to a shoe.

FIG. 7 is a top plan view thereof, shown attached to a shoe.

FIG. 8 is a bottom plan view thereof, shown attached to a shoe.

FIG. 9 is a perspective view thereof.

FIG. 10 is a left side elevational view thereof.

FIG. 11 is a top plan view thereof.

FIG. 12 is an enlarged view of the portion of the shoe heel resembling a taxicab indicated by the box 12 in FIG. 10.

FIG. 13 is a front elevational view of FIG. 9; and,

FIG. 14 is a back elevational view thereof.

The solid black shown in the drawings depicts the color black.

The broken lines in the drawing depict environment and form no part of the claim.

The dash-dot broken lines appearing in FIGS. 3, 4, 10, and 12 depict the cut lines within FIGS. 3 and 10 for the enlarged views shown in FIGS. 4 and 12.

1 Claim, 12 Drawing Sheets
